UNITED STATES PATENT OFFICE.

ISAAC L. SKEITH AND WILLIAM B. BURROWS, OF VANCOUVER, BRITISH COLUMBIA,
CANADA, ASSIGNORS TO SUMNER IRON WORKS, OF EVERETT, WASHINGTON.

POWER LIFTING MECHANISM FOR SAW-TRIMMERS.

1,267,130.

Specification of Letters Patent.

Patented May 21, 1918.

Application filed August 18, 1910. Serial No. 577,855.

To all whom it may concern:

Be it known that we, ISAAC L. SKEITH, a subject of Great Britain, residing at Vancouver, British Columbia, Canada, and WILLIAM B. BURROWS, a citizen of the United States, residing at Vancouver, British Columbia, have invented a new and useful Improvement in Power Lifting Mechanisms for Saw-Trimmers, of which the following is a specification.

Our invention relates to an improvement in power lifting mechanisms for saw trimmers and comprises the novel parts and combinations of parts which will be hereinafter described and particularly pointed out in the claims.

The object of our invention, broadly stated, is to improve and simplify the construction and operation of such devices.

Specifically, our object comprises a construction such that valves controlling the admission and exhaust of air from and supply of air to the lifting cylinders, are placed directly upon the cylinders so that the clearance is minimized and such valves operated from a distant point by a mechanical connection. By this plan the large waste of air caused by the necessity for filling the pipes extending from the cylinders to the central control point every time the saw is lifted, is avoided.

Another specific object of our invention is to provide automatic means, controlled by the valve-controlling mechanism, whereby when a saw is lifted it will be prevented from dropping until the controlling mechanism has been placed in release position, even should the air pressure entirely fall. This comprises a mechanical catch controlled by the means employed for setting the valve so that it and the valve functionally agree.

Our invention also comprises specifically, a construction of operating levers by which each individual saw may be raised or lowered as desired and, in connection with this, a master lever to which any number of individual levers may be connected for simultaneous operation as desired.

Our invention further specifically comprises a novel construction in the means employed for supporting and swinging the saw into and out of operation.

The further objects of our invention will

be disclosed by a study of the specifications and claims terminating the same.

In the drawings we have shown our invention embodied in the form now preferred by us.

Figure 1 is longitudinal section through one of the pneumatic cylinders employed for controlling a saw.

Fig. 2 is a section on the broken line X of Fig. 1.

Fig. 3 is a section on the line Y—Y of Fig. 1.

Figs. 4 and 5 are, respectively, side and end elevations of the bank of controlling levers.

Figs. 6 and 7 are, respectively, side and edge elevations of one of the individual saw controlling levers.

Fig. 8 shows in plan and diagrammatically, the general arrangement of the parts and the connection with the central controlling station.

Fig. 9 shows the arrangement of the entire apparatus in side elevation.

Fig. 10 is a plan view of one of the frames carrying a saw.

Fig. 11 is a side elevation of the swinging saw frame.

Fig. 12 is an end view of the three-armed lever which operates the valve.

Figs. 13 and 14 are, respectively, plan and elevation of catch-releasing cam or tappet.

Fig. 15 is a side elevation of the spring catch for the master lever.

It has been common, heretofore, to control a bank of trimmer saws by supplying the individual frames, which each carries one of the saws, with a pneumatic cylinder so connected thereto that the saw may be lifted into or out of operating position by admitting air to such cylinder. In such devices the valves for the various cylinders have been located at the central controlling point, which point must necessarily be at some distance from the cylinders. Such method means that whenever a cylinder is thrown into operation, the pipe, extending from the central point of control to the cylinders, must be filled with air under pressure, which air is not essential to the proper action of the piston but simply serves to fill the pipe and communicate the pressure, and is wasted every time the cylinder is put into

105

use. As a result there is a large and unnecessary waste of compressed air, making it necessary to employ an air compressor of much larger capacity than would be required if this excessive clearance could be eliminated.

In our present invention we have placed the valves directly upon the cylinders, so that the clearance between the valve and the cylinder is almost entirely eliminated, and then control these valves by mechanical connection with the distant point of control. This results in a material saving in the amount of compressed air required.

In devices of this character it is customary to have the saws mounted in swinging frames so that the saw will drop by gravity into operating position and will be lifted out of operating position by the action of the cylinder thereon.

We have provided means whereby when any individual saw frame is lifted out of operating position, a mechanical catch will be automatically thrown into acting position and so held until the regular controlling mechanism for this saw is placed in release position, so that if the pressure in the cylinder should drop from any cause, such for instance as the stoppage of machinery, the saw will not drop into operative position until such mechanical catch has been released. The use of this catch prevents the belts by which the saws are operated from being strained at their maximum tension when the saws are not in use, which objection applies to such devices as are not positively held out of operative position when the pressure in the cylinder is removed.

We have also provided means for operating the cylinder valve from a distance, such as will permit the connection of the operating means thereto at any angle desired.

In the drawings Fig. 1 shows the longitudinal section of the cylinder with the valve and the means for operating the same. The cylinder 1 is single acting, that is, the power is applied to the piston to move it in one direction only, which as shown is during the upward stroke. The piston 2 may be of any suitable or desired construction.

The cylinder is provided with an inlet port 10, located at the extreme lower end of cylinder, and an exhaust port 11 located some little distance above the lower end of the cylinder and so that it will be covered by the piston in its downward stroke before it can strike the lower head. In this way a certain amount of air contained in the cylinder is trapped and serves as a cushion to prevent the piston from striking hard against the lower end of the cylinder.

To prevent dangerous striking of the piston against the upper cylinder head, we place the relief port 17 a short distance below the cylinder head where it will be cov-

ered by the piston before finishing its stroke thus trapping enough air to cushion the piston. By controlling the size of this port the rate of upward movement of the piston may be controlled, the small port acting to delay the escape of the air.

The piston rod 20 extends through the lower end of the cylinder and is connected with the rod 21 which is in turn secured to the swinging saw frame either directly or by means of interposed mechanism. As shown, the connection consists of a turnbuckle 24 and rod 25.

We have provided means by which the saws will be mechanically locked and held in raised position in case the pressure in the cylinders is dropped below that necessary to support them. The means preferred and herein shown is as follows:

Upon the lower end of the piston rod 20, which projects from the cylinder, is secured a disk or cam 23 the periphery of which is of conical shape with the base downward. We have shown this as being a part of the crosshead or pivotal connection with the rod 21, although this is not an essential feature. The lower surface 22 of this disk is concave near its edge so as to more securely engage with the point of the locking hook. This hook is pivoted at 40 between ears beneath and forming a part of the cylinder. The upper, engaging surface 41 of the hook is slightly recurved so as to coöperate with the curved under surface of the disk 22 and thereby assure against release, once they are brought into engagement except by the positive action of the releasing mechanism. The surface 42 of the side of the hook extending below the engaging surface 41, and facing toward the disk 23 is inclined in such a way that it will coöperate with the inclined or coned peripheral surface of the disk, so that the disk in raising will push the hook outward until it has passed the same, whereupon the hook will swing toward the piston rod under the influence of gravity, the point 41 swinging beneath said disk so as to prevent its falling until the hook has been positively thrown outward.

At its upper end the hook 4 is provided with a side extension having its end surface 43 so inclined and positioned as to engage with the eccentric or cam disk 32 carried by the lower end of the valve 3. When the valve 3 is moved downward into the admission position, the disk 32 frees the hook so that it may drop by gravity into its locking position.

The valve 3, in the form shown and preferred, is a piston valve, consisting of a round bar which is reduced in area at two points 30 and 31, so as to provide a suitable area for the passage of steam between the supply chamber 12 and the port 10, and also

between the two exhaust ports 11 and 13. The position of the valve shown in Fig. 1 is that in which the compressed air is in communication with the interior of the cylinder.

5 Compressed air from the supply chamber 12 passes around the section 30 of the valve to the port 10, and thence directly into the cylinder, acting to raise the piston to the top of the cylinder.

10 The lower end of the valve 3 projects through the walls of the cylinder and has a tappet secured thereto, this as shown consisting of an eccentric or cam disk 32, which, in the admission position of the valve, is engaged by that portion of the inclined surface 43 of the hook, which is nearest the pivot 40.

If now the valve be raised, the first result will be that the movement of the tappet disk 32 over the inclined surface 43 of the hook 20 will swing the point 41 from beneath the disk 23, thus leaving the piston free to fall.

The disk 23 is slightly above the point 41 of the hook when the piston is in its uppermost position, so that the weight of the piston 25 ton and the load carried thereby will never be carried by the hook, unless the air pressure should drop below that required to carry the load. The swinging of the hook clear of the disk does not, therefore, require 30 the use of any material force.

The next result caused by the raising of the valve is to cut off the supply of compressed air to the cylinder by closing the port 10. The valve is given sufficient lap 35 that exhaust does not commence until after the valve has moved a certain distance after closing the admission port. This gives sufficient travel that the hook point 41 is clear of the disk 23 before exhaust commences. 40 This takes place through port 11, about the reduced section 31 of the valve and through port 13.

In order to control the rate of exhaust and prevent the rapid dropping of the piston we provide what may be called a 45 throttle bolt 110, which passes through the wall of the cylinder and into the exhaust port 11. This bolt is clearly shown in Fig. 3. It is evident that by screwing this bolt 50 inward it will reduce the area of this exhaust port, which reduction of area may be carried to such a point as will throttle the exhaust so as to make the rate of fall of the piston whatever desired.

55 The saws are mounted upon swing frames in such a manner that when the saw is raised out of operative position the belts are slackened, and when they are dropped into operative position the belts are tightened, consequently if the saws be maintained in their raised position, in which the belts are slackened, by positive mechanical means in which position the belts are freed from strain, it will not be necessary to cut 60 and tighten them at frequent intervals, and

they will therefore last much longer. These mechanical locking means above described are controlled directly by the action of the valves controlling the power mechanism, being freed as the first step of the movement of the valve mechanism to its release position.

To the upper end of the valve 3 which extends to the exterior of the valve chamber is secured a rod 33 by which the valve is 75 operated. We have provided a means for operating these valves which will permit of leading the actuating wires in any angular direction desired. These means comprise an arm which is pivoted in direct line 80 with the axis of the valve and upon which is mounted a double elbow or three-armed lever, one end of which is connected with valve rod 33, the pivot connection being in line with the axis of the valve and in line 85 with the pivot of this swinging arm.

At the end of the cylinder opposite that which contains the valve and in line with the axis of this valve is mounted a pivot bolt 50 upon which is pivoted an arm 5. 90 This arm is preferably made hollow and, as shown, between the sides thereof is placed a double elbow or three armed lever 6, one arm 60 being pivotally connected with the upper end of the rod 33 and of such length 95 as to move in a small arc which does not materially diverge from an exact alignment with the axis of the valve.

The arms 62 and 63 of these levers extend oppositely from the central pivot 61 and 100 are provided with the means at each end, consisting of holes or projecting pins, 64, to which may be connected whatever means are employed for communicating the motion thereto from a distant point.

The means preferred by us for this purpose consists of small piano wires, which may be conducted around corners in any course desired by means of simple guide pulleys. We prefer to provide the swinging pivot arm 5 with stops which will be 110 engaged by the elbow lever 6, so as to limit its motion in any direction. Such stops, as shown, consist of set screws 51 screwed through a portion of the lever in a position 115 to be engaged by arms 62 and 63 of lever 6. Two wires 52 and 53 are connected with the opposite arms of each of these levers and lead to the central control point.

At a central control point is provided a 120 bank of controlling levers, one for each cylinder employed, which levers are each connected by means of these wires with its respective lever 6 carried by the cylinders. We also provide a master lever and means 125 by which any number of individual levers may be connected so as to be operated by and in unison with the master lever.

These operating levers are shown in Figs. 4, 5, 6, and 7. Both individual levers and 130

the master lever are pivoted upon a common shaft 7, which shaft is supported by brackets 70 or in any other suitable manner. The individual levers 71 are provided with arms 72 which extend oppositely from the pivot, and to the outer ends of which are connected the wires 52 and 53, which extend to the levers 6 mounted upon the different cylinders. The levers 71, by which the individual saws are operated, are mounted loosely upon shaft 7.

Secured to the shaft 7, preferably at each end thereof, are master levers 8. These master levers are also connected by a rod 80 which extends through slots 73 formed in each one of the individual levers 71. These slots 73 are of sufficient transverse length to permit of each lever being operated so as to control its valve, without moving the master lever.

These slots in the lever may be made of a permanent character closed at each end. We prefer, however, to make them open at one end and then provide means, for instance 25 the pivot latches 74, by which this end may be made open or closed as desired. Such levers as have their latches 74 in position to close the slots will be operated simultaneously by movement of the master lever 30 in either direction, while such levers as have their latches dropped, so as to leave these ends of the slots open, would not be operated by movement of the master lever in one direction. It often happens in operating a 35 bank of trimmer saws that it is desired to operate certain combinations of saws simultaneously.

The above expedient makes it possible for the operator to connect any combination as 40 is desired for simultaneous operation by the master lever and to vary this combination at any time desired. By moving the master lever in the direction in which all the slots 73 are permanently closed, all the saws will 45 be raised while movement in the opposite direction will lower only those saws whose individual levers have their latches 74 in position to close their slots.

In operating a master lever this must be 50 given a movement sufficient to engage the rod 80 with the end of the slots in the individual levers before any movement of the valve is started. The master lever, therefore, has a greater swing than the individual 55 levers.

In Fig. 5 the lever 71 is shown in full lines in one extreme position and by dotted lines in the other extreme position. The master lever is shown in full lines in its inoperative or central position and by dotted lines in both extreme or operating positions. The master lever is provided with means by which it is held in central position until it is desired to move it; such means as shown 65 consisting of a pin 81 projecting laterally

from the lever and a spring catch 82 having a recess or hollow 83 adapted to engage such pin and furnish sufficient resistance to prevent movement of the lever unless some little power is applied thereto.

In Fig. 8 we have shown a number of cylinders 1 connected by means of unions 11 and short pipe sections 15, with a main supply pipe 16. This makes a very simple and cheap method of supplying the air to these 75 cylinders as compared with the plan having separate supply pipes from the central control station to each cylinder. We also show a series of wires 52 leading from these cylinders to a central controlling station A. 80 This view is very diagrammatic in character.

In Fig. 9 is shown, in elevation, the entire apparatus. The wires 52, 53, may be led about wheels or pulleys 54 to the central 85 controlling station 103 where they are connected with the arms 72 of the individual controlling levers. Each wire should have a turnbuckle 55 therein so that its length may be adjusted.

In Figs. 10 and 11 we have shown a plan for mounting saws in swinging frames which permit of adjustment to take up the stretch occurring in the driving belt, as well as for alining the saw so as to get exact 95 spacing between the saws of the set. This mechanism comprises a frame 9 in one end of which a saw, 100, is mounted, which frame is pivoted at 90 to arms 91 which are pivoted at their upper ends by pivots 92 to 100 brackets 93 secured to the end timber 94.

The driving pulleys 95 for all the saws of the set are mounted upon a shaft 96 which is journaled to the timber 94. To the lower pivot 90 of this device is secured eye bolts 105 97, which pass through openings in the timbers and are provided with nuts 98, by the adjustment of which these eye bolts may be projected or withdrawn as may be necessary for lengthening the belts, or adjusting 110 the position of the saw relative to the other saws. The lateral adjustment or alinement of the saws is varied by unequal adjustment of the bolts 97. Adjustment of the bolt 97 at one side of the frame without any adjustment of the corresponding bolt upon the other side would swing the outer end of the saw frame laterally.

The shaft 96 is higher than the pivot 90 so that when the frame 9 is raised it will 120 tend to slacken the belt 99 by which the saw is driven. When the frame is lowered to place the saw in operative position the belt is tightened. As the saws occupy the raised position more time than they do the lowered 125 position the life of the belts is thereby much increased.

We claim as our invention:

1. A lifting mechanism for trimmer saws, comprising a series of cylinders and pistons 130

- therein, each connected with its individual saw, a valve carried by each cylinder and adapted to control the piston therein, a series of levers and connections therefrom, 5 each to its particular cylinder valve, each of said levers having a transverse slot, a master lever, and a rod carried by said master lever and adapted to lie in said slots of the individual levers, whereby the individual levers 10 may be operated separately and a series of said individual levers may be operated simultaneously by the master lever.
2. The combination with a series of saws, of saw-lifting mechanism comprising a corresponding series of compressed air cylinders each having its piston connected with its saw, valves mounted adjacent to the cylinders, respectively, and each controlling the piston-actuating fluid for its cylinder, 15 and manually operated means at a distant station for controlling all said valves.
3. A lifting mechanism for saw trimmers, comprising a series of cylinders and pistons therein each connected with its individual saw to raise and lower the same, valves mounted adjacent to said cylinders, respectively, and controlling the fluid for actuating the corresponding pistons, means for mechanically transmitting power from a distant station to each of said valves, and manually operated selective devices at said station for governing the transmission of power to the several valves.
4. A lifting mechanism for trimmer saws, comprising a series of cylinders and pistons therein, each connected with its individual saw, a valve carried by each cylinder and adapted to control the piston therein, a series of levers and connections therefrom, 20 each to its particular cylinder valve, and a master lever whereby the saws may be raised and lowered at will individually or collectively.
5. A lifting mechanism for trimmer saws, comprising a series of cylinders and pistons therein, each connected with its individual saw, a valve carried by each cylinder and controlling the movement of the piston therein, a series of distant controlling levers, 25 a connection from each of said levers with the valve of its particular cylinder, said levers each having a transverse slot provided with means whereby one end of said slot may be closed or opened at will, and a master lever whereby the saws may be raised and lowered at will individually or collectively.
6. A lifting mechanism for trimmer saws, comprising a series of saws, means for supporting and swinging the saws into and out 30 of position independently of each other, a series of operating levers corresponding with the saws, and a master lever whereby the saws may be raised and lowered at will individually or collectively, a cylinder with 35 piston mounted above each saw, a valve upon each cylinder for controlling the piston and connected by actuating wires to their respective levers located at a distant point of control.
7. A lifting mechanism for trimmer saws, 70 comprising means for moving the saws into and out of operating position, a separate cylinder and piston for each saw, and a controlling valve mounted on each cylinder, a series of operating levers and a master lever 75 located at a distance from said cylinders, and mechanical valve-operating connections, as a wire, extending from each operating lever to its respective valve.
8. In a lifting mechanism for trimmer saws, a cylinder and piston therein for each saw, said cylinders having the seats for the fluid controlling valves formed integrally therewith, a valve for each cylinder coacting with the seat for said cylinder, and means 80 for controlling said valves from a common point.
9. In a lifting mechanism for trimmer saws, a separate cylinder and piston therein for each saw, said cylinder having a valve 85 seat formed therein, a valve in said seat, a valve operating lever mounted upon the cylinder to swing upon double pivots having axes which are at substantially right angles, distant operating means, and transmitting mechanisms connecting said operating means with the cylinder-carried, valve-operating levers and radiating from a common point to the various cylinders.
10. In a lifting mechanism for trimmer saws, a separate cylinder and piston therein for each saw, each cylinder having a valve seat formed thereon, a valve seating upon said seat, and a valve-controlling member carried by the cylinder, said valve-controlling member being automatically adjustable 100 to conform to the lead of a transmission member throughout a wide angular range.
11. In a lifting mechanism for saw trimmers, the combination with separate actuating mechanisms for each saw, each of said actuating mechanisms comprising a cylinder and piston, a valve controlling the actuating fluid and a means for controlling said valve, 105 all mounted directly upon the cylinder as a frame, of a corresponding set of distant secondary controlling mechanisms, one for each cylinder, transmission members connecting said secondary controlling members with the primary valve-controlling members 115 carried by the cylinders, a master controlling member associated with said set of secondary controlling members, and means for optionally combining said secondary controlling members for simultaneous operation 120 by said master member in any combination desired, without affecting their capacity for independent and separate action.
12. A shifting mechanism for trimmer saws comprising a series of saw shifting 125

6
cylinders, a valve seated in the body of each of said cylinders and controlling the supply of motive fluid, each for its respective cylinder, and a selective operating mechanism for said valves located at a common point.

13. A shifting mechanism for trimmer saws comprising a series of saw shifting cylinders, a valve seated in the body of each of said cylinders and controlling the supply of motive fluid, each for its respective cylinder, a valve shifting mechanism for each cylinder pivotally mounted upon that cylinder to automatically adjust itself to an actuating connection from variable angles, manually controllable actuating members grouped at a common point and transmitting members connecting said manually controllable members with the valve shifting mechanism carried by the cylinders, and means for combining said manually controllable members to actuate any desired combination thereof as a unit.

14. A shifting mechanism for trimmer saws comprising a series of saw shifting cylinders, a valve seated in the body of each of said cylinders and controlling the supply of motive fluid, each for its respective cylinder, a valve-shifting mechanism for each cylinder pivotally mounted upon that cylinder to automatically adjust itself to an actuating connection from variable angles, manually controllable actuating members grouped at a common point and transmitting members connecting said manually controllable members with the valve-shifting mechanism carried by the cylinders.

15. A lifting mechanism for trimmer saws comprising a cylinder, a piston therein, a piston rod, a connection from the exterior end of said rod to the saw frame to lift it, a dog engaging member or catch carried by the outer part of the piston rod, a dog piv-

oted to the cylinder and adapted to swing under said catch member by gravity, and means for releasing said dog from the catch actuated by the valve which controls the supply of actuating fluid to the cylinder.

16. In a lifting mechanism for trimmer saws, a cylinder, a piston therein, a valve controlling the actuating fluid, means connecting the piston with the saw, a mechanical catch comprising one member carried by the cylinder and another connected with the piston and adapted for automatic locking engagement, and means for operating both valve and catch from a distance.

17. In a lifting mechanism for trimmer saws, a cylinder, a piston therein, a valve controlling the actuating fluid, means connecting the piston with the saw, a mechanical catch comprising one member carried by the cylinder and another connected with the piston and adapted for automatic locking engagement, means for operating the valve from a distance, and means whereby the movement of the valve into exhaust position will release the catch.

18. In a lifting mechanism for trimmer saws, a fluid pressure cylinder, a piston therein, a piston rod, a valve carried directly upon that end of the cylinder from which the piston rod projects, a locking catch automatically engageable to hold the piston when raised and comprising one member carried by the piston rod and another carried by the cylinder, one of said catch members and the valve having parts engaging to release the catch when the catch is placed in release position.
